UNITED STATES PATENT OFFICE.

JAMES HOWARD DICKERSON, OF DANVILLE, VIRGINIA, ASSIGNOR OF ONE-HALF TO B. S. MOTLEY, OF SAME PLACE.

SASH-LIFT.

SPECIFICATION forming part of Letters Patent No. 623,890, dated April 25, 1899.

Application filed March 20, 1897. Serial No. 628,494. (No model.)

To all whom it may concern.

Be it known that I, JAMES HOWARD DICKERSON, a citizen of the United States, residing at Danville, in the county of Pittsylvania and State of Virginia, have invented certain new and useful Improvements in Sash-Lifts; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to those sash-lifts operated by a pulley-and-weight mechanism from the side of the window-frame.

The object of my invention is to produce a more simple, cheap, and durable mechanism 20 which can be more easily operated, more positive in action, and which will avoid the use of pawl-and-ratchet or other fastening devices for retaining the sash at the various heights desired.

25 To this end my invention consists in the peculiar features and combinations of parts more fully described hereinafter and pointed out in the claim.

In the accompanying drawings, Figure 1 30 represents the front elevation of my complete device as applied to an ordinary window having upper and lower sashes, the frame being cut away to disclose the parts within; and Fig. 2, an edge view of the window-frame, 35 showing the position of the parts connected to the lower sash when the latter is down.

The reference-letter *a* denotes an ordinary window-frame provided with upper and lower sashes *b* and *c*, movable vertically therein. 40 The opposite sides of the frame are provided with the usual chambers *d*, in which the sash-weights operate. As each of the two sashes shown are provided with independent devices for operating them a description of the mechanism for one of the sashes will suffice for both. The upper sash *b* is actuated by a windlass mechanism located in the chamber *d* at the right-hand side of the frame. This mechanism consists of a drum or spool *e*, located a slight distance above the window-sill,

with its axis extending transversely through the frame.

g represents a crank-handle on the windlass. This crank-handle is located on the outside of the window-frame within the house, 55 so that the sash can be raised and lowered without putting one's hand outdoors and exposing it to the weather.

h represents an endless cable which is given several winds or coils around the drum, 60 whence it passes up around the pulley *i*, suspended from the top wall of the chamber *d*.

j represents a counterbalancing-weight which is attached to the endless cable to move up and down between the pulley and windlass. 65

The sash *b* is connected to the weight by a cord *k*, which passes over the pulley *l* in the frame *a*. The opposite or left-hand side of the sash *b* is provided with the usual counterbalancing-weight *m*, pulley *n*, and cord *o*. 70 The lower sash *c* is raised and lowered through the medium of a windlass mechanism operated by an externally-projecting crank-handle *g'*, all of which is arranged exactly like the mechanism just described on the right-hand side of the frame. The right side of the lower sash *c* is provided with a counterbalancing-weight *m'*, which moves up and 75 down with the rise and fall of the sash in the right-hand chamber *d* and alongside of the counterbalancing-weight *j*. This weight is made heavier than the weight *m* on the opposite side of sash *b* in order to facilitate the lowering operation. The cable may be composed of cord, rope, chain, metal strap, or any 80 suitable well-known flexible device to connect the weights with the sashes, and I have therefore used this term merely for convenience.

Having thus described the preferred construction of my invention, I will now proceed 90 to set forth the manner in which it operates. When it is desired to lower the upper sash *b*, the crank-handle *g* should be turned from left to right, thereby revolving the drum *e* in the same direction, winding the right-hand strand and unwinding the left-hand strand of the cable *h*, so that the right-hand strand moves downwardly and the left-hand strand moves upwardly, thus lifting the weight *j* up 95 until the sash rests upon the sill. A contrary 100

revolution of the drum will cause a contrary movement of the cable, thereby lowering the large weight *j* and raising the sash *b*. In this latter movement of the drum the weight is drawn down positively by that portion of the cable which lies between it and the drum, so that a sure and certain movement is effected whether the weight be too heavy or too light. Hence it will be seen that a positive draft is brought on the sash in the lifting operation in addition to that produced by the gravity of the weight. In the upward movement of the weight the upper strand of the cable lying between the weight and the pulley above draws on the weight, lifting it entirely free from the sash, so that the latter moves down with much greater and certain action.

It is evident that my invention can be varied in many slight ways which might suggest themselves to a skilled mechanic without departing from the scope and spirit of the device. Therefore I do not limit myself to the

exact construction herein shown and described, but consider myself entitled to all such variations.

What I claim as new, and desire to secure by Letters Patent, is—

The combination with a window frame and sash, of a weight and weight-cord connected with the sash and running over a sheave *n*, and endless cord connected with the weight-cord and passed over sheave *i* and drum, and means connected with the inner end of the drum for rotating it positively in either direction whereby the weight-cord may be raised or lowered with the attached sash to any predetermined elevation without the necessity of touching the window-sash.

In witness whereof I affix my signature in presence of two witnesses.

JAMES HOWARD DICKERSON.
